UNITED STATES PATENT OFFICE.

LEONARD MARKELS, OF NEW YORK, N. Y., ASSIGNOR TO CHAMPION GRAPHAPHONE COMPANY, INC., OF NEW YORK, N. Y.

DESIGN FOR A PHONOGRAPH BOX OR CABINET.

48,188.

Specification for Design.

Patented Nov. 23, 1915.

Application filed May 18, 1915. Serial No. 28,980. Term of patent 3½ years.

To all whom it may concern:

Be it known that I, LEONARD MARKELS, a citizen of the United States, and a resident of the city of New York, borough of Manhattan, in the county and State of New York, have invented a new, original, and ornamental Design for a Phonograph Box or Cabinet, of which the following is a specification, reference being had to the accompanying drawing, forming part thereof.

The figure is a perspective view of a phonograph box illustrating my improved design.

I claim:

The ornamental design for a phonograph box or cabinet, as shown.

LEONARD MARKELS.
